Primary Examiner — Melanie H Tung*(74) Attorney, Agent, or Firm* — Banner & Witcoff, Ltd.**CLAIM**

The ornamental design for a display screen with a graphical animated user interface, as shown and described.

DESCRIPTION

The FIGURE is a front view of a display screen with a graphical animated user interface showing the new design. The broken line showing of the remainder of the graphical user interface and the display screen is for environmental purposes only and forms no part of the claimed design.
